FLAME-OPERABLE SWITCH

James J. Anderton, Weldon, N. C., assignor of one-half to Abraham Elias, Weldon, N. C.

Application September 21, 1939, Serial No. 295,954

3 Claims. (Cl. 200—142)

This invention relates to a switch construction adapted for use in connection with fire-alarm systems and it aims to provide a novel, inexpensive and efficient construction adapted for use at various locations in buildings such as the home, factory, office, store and auditoriums or otherwise, and even in vehicles, so as to be operable by a flame or heat in the event of a fire, to close such switch to operate a siren, fire-alarm or other audible signal or means.

It is further aimed to provide such a construction wherein the circuit is normally held open by fusible means.

The more specific objects and advantages will become apparent from a consideration of the description following taken in connection with accompanying drawing illustrating an operative embodiment.

In said drawing—
20 Figure 1 is an inverted plan view showing the improved switch;

Figure 2 is a side elevation thereof;

Figure 3 is a vertical section taken on the plane of line 3—3 of Figure 1;

25 Figure 4 is a vertical section taken on the plane of line 4—4 of Figure 2;

Figure 5 is a horizontal section taken on the plane of line 5—5 of Figure 2, and

Figure 6 is an electric diagram showing the 30 employment of the switch in a fire-alarm or equivalent electric circuit.

Referring specifically to the drawing wherein like reference characters designate like or similar parts, a body or block of insulation is provided at 10 adapted to be mounted in any suitable manner as by means of fastenings 11, passed through openings in ears 12 integral with such body. Across one face of the block 10, for instance the bottom face, a pair of parallel grooves 13 are cut in which portions of conductor wires 14 are disposed. Such wires 14, as suggested in Figure 6, are adapted to be connected in parallel in an electric circuit including an audible member 15, such as a fire-alarm, siren, signal or the like. By way of example, that portion of the circuit containing the wires 14 has a secondary coil 16 of a transformer 17, the primary coil of which is shown at 18 and adapted to receive its current or energy from any desired source. All 40 exposed portions of the conductors 14 as usual are covered with suitable insulation as at 19. Said conductors 14 are held against displacement from the grooves or slots 13 by means of screws 20 which are threaded into the block or body 10 and cross such slots 13.

The circuit through the alarm or other member 15 is normally open but is adapted to be closed at a predetermined temperature of the surrounding air and by contact of a flame with the switch. To this end, a metallic or other plate 21 is 5 fastened or positioned across the bottom of the block 10, being held in place for example by a screw 22, threaded to the block. A switch rod 23 is secured against the inner surface of the plate 21 as at 24 by a suitable solder or fusible material, adapted to melt at a predetermined temperature and especially in the presence of a flame, whereby it will be automatically released and detached from the plate 21.

It will be noted that the bottom face of the 15 block 10 has a slot or groove 25 therein at a right angle to the slots 13 and in which said rod 23 is free for movement to bridge the conductors 14, when separated from the plate 21.

An opening or recess 26 is provided through the 20 block 10 and it communicates with the slot 25. In such recess 26, a contractile coil spring 27 is housed which has a hook 28 at its lower end in engagement with the rod 23 and attachment of which hook to the rod is facilitated by a slit 29 in 25 the plate 21 extending inwardly from one end thereof, transversely of and past the rod 24. The other end of said spring 27 has a hook 30 which is engaged with an anchoring rod 31 disposed in a transverse slot 32 of the block and 30 open at the top thereof.

As a result of the construction described, it will be realized that although one of the switches is shown, any desired number of them may be arranged in the same electric circuit and that they 35 may be arranged at any desired location within the room of a home, office, factory, auditorium or elsewhere, or arranged at different locations within a vehicle containing an alarm system or otherwise, so that in the event of fire, the switch 40 closest to the flame, will be subjected to the heat thereof in order to melt the fusible material 24, thus freeing the rod 23 so that the contractile action of the spring 27 will thereupon move the rod into bridging relation with the conductors 14 45 and effect the alarm, signal or the like at the instrument 15, giving warning of the fire and enabling those within the fire danger zone, to seek a place of safety.

Various changes may be resorted to provided 50 they fall within the spirit and scope of the invention.

I claim as my invention:

1. A switch of the class described comprising a 55 block having spaced conductors thereon, a switch

closing member engageable with the conductors, spring means urging said member toward the conductors, a mounting for the switch closing member, fusible means connecting said switch closing member to the mounting, said spring means having a hook engaging the switch closing member, and said mounting having a slit enabling application of the hook to the switch closing member.

5. A switch of the class described comprising a block having spaced conductors thereon, a switch closing member engageable with the conductors, spring means urging said member toward the conductors, a mounting for the switch closing member, fusible means connecting said switch closing member to the mounting, said block having 10 slots crossed by the switch closing member and in which said conductor members are dis-

posed, and said mounting member closing said slots.

3. A switch of the class described comprising a block having spaced conductors thereon, a switch closing member engageable with the conductors, 5 spring means urging said member toward the conductors, a mounting for the switch closing member, fusible means connecting said switch closing member to the mounting, said block having slots in which said conductor members are 10 disposed, said mounting member closing said slots, a rod crossing the end of the block opposite to the mounting and to which one end of said spring is connected, and fastening members on the block crossing the first mentioned slots to retain the conductors therein. 15

JAMES J. ANDERTON.
